UNITED STATES PATENT OFFICE.

LESLIE W. CLAYBOURN, OF MENASHA, WISCONSIN.

METHOD OF CORRECTING PRINTING PLATES AND PRINTING PLATES PRODUCED THEREBY.

Application filed March 19, 1921. Serial No. 453,665.

to all whom it may concern:

- Be it known that I, LESLIE W. CLAYBOURN, a citizen of the United States, residing at Menasha, in the county of Winnebago and State of Wisconsin, have invented certain new and useful Improvements in Methods of Correcting Printing Plates and Printing Plates Produced Thereby, of which the following is a specification.
- 10 It is the object of my invention to provide a new and improved method of correcting printing plates, whereby to minimize or substantially reduce so-called make-ready on the printing press, and is applicable to flat printing plates and also to curved printing plates, although portions of my invention are especially employable in connection with curved printing plates.
- 15 It is the object of my invention to bring all portions of the printing surface into the projection of the same surface, that is, into the same plane if the plate be a flat plate, and into the same surface of the sector of a cylinder if the plate be a curved plate, as determined by printing pressures; further, to compress the backing of a printing plate in order to impart to the same a greater density than when the plate is first formed; further, to compress a printing plate for correction of its printing surface with pressure greater than the printing pressure applied to the plate; further, to cause differential compression of the backing of the printing plate according to the solidities of the various portions of the printing surface of the printing plate; further, to provide the different portions of the printing plate with different densities according to the solidities of the corresponding portions of the printing surface thereof; further, to compress the backing of a printing plate with greater density at its solid printing portions than at its high-light or lighter printing portions; further, to correct a printing plate by pressing those portions thereof which print with too light an impression toward the printing surface of the printing plate and then bringing, as by shaving, the various portions of the rear face of the backing into the projection of the same surface, that is, into the same plane in the case of a flat plate and into the same cylindrical projection in the case of a curved plate; further, to determine the correctness of the portions of the printing surface by means of a proof obtained by mounting the printing plate upon a substantially unyieldable surface, for instance metal, and backing the proof sheet by a substantially unyieldable surface, for instance metal, so as to obtain all portions of the proof between substantially unyielding surfaces, which throughout their areas are equidistant; further, to compress the backing of the printing plate while confining said backing as a whole in the plane of the plate; further, to compress the backing of a printing plate while maintaining the printing lines in their original printing distance relations in the printing surface, further to compress the backing of a printing plate substantially immediately after casting the same or before the metal thereof has acquired the hardening which it acquires by lapse of days of time; further, to compress the backing of a printing plate in manner to avoid stretching of its printing surface; further, to compress a printing plate by pressures directed in a direction substantially perpendicular to the printing surface of the printing plate and in manner to maintain the distances, parallel with the printing surface, between the printing lines; further, to press the sunken or concave printing portions of the printing surface located between printing edges into the plane of said printing edges; and, further, to reduce a printing plate to uniform thickness and different densities at its printing portions.
- 20 It is the object of my invention, further, to press portions of the printing surface of a printing plate which appear too light in the proving of the printing plate toward the projection of the printing surface of the printing plate and then reduce said pressed portions and the balance of the printing portions of the printing plate to a uniform thickness, reproving the same, and again pressing the portions of said printing plate which appear too light, if any, there be, toward the projection of the printing surface of the plate, and reproving the same, in repeated sequences, as determined by the proving thereof, routing out the portions of

said plate which are not to be printed and removing the bearers thereof if any there be, and again proving the plate, and correcting the plate in manner mentioned, if necessary or desirable. I have found in practice, however, that compression of a printing plate by my improved method is ordinarily sufficient to render the printing surface thereof in substantially proper printing conditions, and that ordinarily little subsequent correction is required to render the plate properly printable.

I have found further, that when printing from plates as heretofore made, the printing surface of the plate will let down or the backing thereof compress in uneven manner away from the printing surface to cause imperfect printing. It is a further object of my invention, therefore, to compress the printing plate and especially the backing material thereof to a density at least as great as any density which might be imparted to the printing plate or its backing by printing pressures, especially at the solid portions of its printing areas.

It is the object of my invention, further, to produce an improved printing plate embodying the characteristics and advantages due to employment thereon of my improved method.

I have exemplified my invention as employing certain machinery and tools, although it is obvious that these may be wholly or partially dispensed with or changed or other machinery and tools employed within the spirit of my invention within the scope of the appended claims.

In the drawings:

Fig. 1 represents a plan view of an exemplifying printing plate.

Fig. 2 is a cross-section of the same taken on the line 2—2 of Fig. 1.

Fig. 3 represents a cross-section of a portion of the printing plate shown in Fig. 1, taken on the line 3—3 of Fig. 1, to illustrate the usual relations between the printing surface and the backing surface in their crude state, as in present methods, the plate being shown enlarged to disclose imperfections inherent in such plates.

Fig. 4 is a cross-sectional view of the same plate, taken on the same section line as in Fig. 3, the plate being shown subjected to compression by means of a compressing member, such as I prefer to employ, for compressing the printing plate.

Fig. 5 is a front elevation of an exemplifying machine, partly broken away, for compressing the printing plate.

Fig. 6 is a plan view of one corner of the compressing member.

Fig. 7 is a plan view of a portion of an exemplifying compressing member for printing plates having a preponderance of solid printing portions.

Fig. 8 is a cross-section of the same, taken on the line 8—8 of Fig. 7.

Fig. 9 is a plan view of a similar compressing member for printing plates having a preponderance of high-lights or lighter printing portions in the printing surface thereof.

Fig. 10 is a cross-section of the same, taken on the line 10—10 of Fig. 9.

Fig. 11 is a plan view of a portion of an exemplifying compressing member having connected pressing faces.

Fig. 12 is a cross-section of the same, taken on the line 12—12 of Fig. 11.

Fig. 13 is a plan view of the compressed backing of the printing plate illustrated in Fig. 4, partly broken away.

Fig. 14 is a vertical sectional view illustrating the shaving of the backing of the printing plate while flat, illustrated as accomplished by an exemplified machine shown in longitudinal vertical section.

Fig. 15 is an end elevation of the same.

Fig. 16 is a vertical sectional view illustrating the proving of the printing plate while flat, the exemplifying machine therefor being shown in longitudinal section.

Fig. 17 is a cross-sectional view illustrating the curving of the printing plate.

Fig. 18 is a front elevation illustrating an exemplifying machine for compressing a curved printing plate.

Fig. 19 is a side elevation thereof.

Fig. 20 is a vertical cross-section of the same, taken on the line 20—20 of Fig. 19, illustrating the compressing of a curved printing plate.

Fig. 21 is a vertical axial section of the same, taken on the line 21—21 of Fig. 18, partly broken away.

Fig. 22 is a vertical section of a detail of the same, taken on the line 22—22 of Fig. 21.

Fig. 23 is a perspective view of a detail of the same.

Fig. 24 is a cross-sectional view illustrating the shaving of the backing of the compressed curved printing plate.

Fig. 25 is a cross-section of an exemplified device for trimming off the marginal bearer portions of the curved plate.

Fig. 26 is a cross-section of an exemplified device for trimming the ends of the curved plate after its marginal bearer portions have been removed.

Fig. 27 is a vertical sectional view illustrating the proving of the curved printing plate, the exemplifying machine thereof being shown in longitudinal vertical section.

Fig. 28 is a cross-sectional view illustrating the local correcting of the curved printing plate.

Fig. 29 is a vertical longitudinal section of the same, taken on the line 29—29 of Fig. 28.

Fig. 30 is a plan view of a portion of the

backing of a curved printing plate having the locally corrected portion therein.

Fig. 31 is a cross-sectional view illustrating the imposing of the curved printing plate on a convexly curved saddle.

Fig. 32 is a side elevation of the same, partly broken away, and partly in vertical longitudinal section, taken on the line 32-32 of Fig. 31.

Figs. 33 to 36 inclusive, Figs. 38 to 43 inclusive, Figs. 45 to 47 inclusive, and Figs. 49 to 52 inclusive, represent face views showing the impressing portions of impressing faces of a series of small tools, such as I prefer to employ in local corrections of the printing plate, these views having indicating marks in connection therewith to indicate their straight axes or their curved axes.

Figs. 37, 44, and 48 represent side elevations of the tools, whose impressing faces are shown in Figs. 36, 43 and 47, respectively.

Fig. 53 is a side elevation of a blunt-pointed small impressing tool.

Fig. 54 is a side elevation of the small tool whose impressing face is illustrated in Fig. 52; and

Fig. 55 is an end view of the same.

It has heretofore been a usual practice in making ready for the printing from printing plates, to overlay the tympan of the printing press on which the plates are to be printed at those portions at which the printing appears too light in the proofs, or to underlay the printing plate at such portions, or to both overlay and underlay at the insufficiently printing portions, with the result that uneven surfaces are obtained both in the tympan and at the bottom of the printing plate, such system making it necessary also to employ a comparatively soft tympan. Other systems have attempted to produce the differences between solid and high-light printing effect by locating the high-light printing portions of the plate lower than the solid portions, if a flat plate, or nearer the axis of the plate cylinder if a curved plate, this system also producing unevenness of printing surface. These uneven, waving or undulating surfaces at the rear face of the printing plate, or at the face of the tympan, or both, also, in the course of printing, or during a long run, vary from their original states, especially under the heavy print-pressures necessary to be employed under such old methods, resulting in differences in appearance of the printing during different portions of the run and making subsequent make-readies necessary.

I avoid all these objections by bringing the printing surface of the printing lines and areas throughout the printing plate equidistant from the rear or supporting surface of the printing plate, and bringing these two surfaces respectively within the

same projection of a given surface. I am enabled thereby to bring the backing or supporting surface and the printing lines into coaction with surfaces which are equidistant from each other and located in the same 70 projections respectively of two spaced-apart surfaces, namely, the surface of the plate bed or plate cylinder of the printing press and the surface of a coacting comparatively hard tympan sheet. I am thereby enabled 75 to produce superior printing, and also to print with a tympan whose impress surface is throughout substantially the projection of the same surface, so that successive printings by different plates or printing elements 80 may be received by the same portions of the tympan, whereby my invention is especially adaptable for so-called wet printing, in which successive printings in different colors are printed upon the same sheet during 85 its single passage through the printing press, as well as to all other characters of printing, enhancing the appearance and beauty of the printing and enabling me to reproduce the appearance of solids, highlights and intermediate printing effects, in 90 highly contrasted relations in the printing from coordinated plates representing different colors, and avoiding the humps and hollows in the make-ready for one color which 95 are detrimental to the make-ready for another color in the old methods mentioned, and enhancing true registry of the printing lines.

My invention further enables printing to be accomplished with considerably lighter printing pressures and with harder tympans than under such older methods now in general use, and materially increases the numbers of imprints which can be obtained from one make-ready of the printing subject. By my improved method, further, those portions of the printing plate subjected to pressures over the greater areas at the printing surface, namely, the solid portions of the printing plate, are compressed to greater extent than the high-light or lighter printing portions of the plate, and printing plates are produced which retain their clarity of 100 printing effect throughout long periods of 105 use.

The distances and projections mentioned are intended to be measured by print-pressures as they are ordinarily too refined for 110 observation by the naked eye.

The printing plate is exemplified at 51, and in the present exemplification comprises a printing shell 52, which may be of usual electro-deposited metal, for instance, copper deposited on the matrix in electro-plating, and a backing 53 on which the printing shell is fixedly supported, usually cast into the shell. This backing is usually a composition composed for example of lead, tin and antimony, in the proportion, for ex- 115 120 125 130

ample, of ninety pounds of lead and five pounds each of tin and antimony. It is obvious however, that other backing material may be employed and that my invention is not limited to printing plates thus formed.

In carrying out my improved method, the printing plate may at its margins be provided with bearers 55, which may if desired be separated from the printing surface by grooves 56, and the printing plate may also have intermediate or interior bearers, exemplified at 57. The marginal bearers and intermediate bearers may be so associated as to make it advisable to merge the same, as shown at 58. These bearers are useful for receiving the compressive strains at the edges of the plates, and in intermediate portions of the plate which would otherwise be devoid of support in the plane of the printing surface. These bearers are removed from the plate in the course of operation on the plate by my improved method, as hereinafter explained, the marginal bearers being removed, as by sawing, and the interior bearers being removed, as by routing, the latter operation leaving spaces in the face of the plate free of printing function. My improved method is however employable on plates which are not provided with bearers.

I have in Fig. 1 shown an exemplification of the printing face of a printing plate to be corrected, illustrating the differences in solidities of the printing portions of a printing plate, and its bearers. In this exemplification the part 61 represents a solid portion, the parts 62 intermediate portions, and the parts 63 high-light portions of the printing surface.

One of the characters of printing plates upon which my present invention is employable, is shown, described and claimed in my Letters Patent No. 1,318,967, dated October 14, 1919, for method of curving printing plates and printing plates curved thereby.

In my improved method, the printing plate is either formed of approximate uniform thickness, or reduced therefrom, as by approximately straightening the same at its printing surface and shaving the rear face thereof. The approximate straightening of the printing surface may be accomplished by laying the printing plate printing face down on a substantially heavy metal slab having a plane imposing surface and pounding the back of the printing plate through the medium of a usual imposing block and mallet.

The shaving may be accomplished by any usual means, and I have shown an illustrative machine of this character in Figs. 14 and 15, in which 65 represents the bed of the machine, which bed is for instance of metal having a plane surface. A carriage

66 has thereon knife-sections 67, between which bearing rollers 68 are located to press the printing surface of the printing plate toward the bed. The carriage is suitably driven, as by means of a pinion 71 at each side of the carriage, fixed to a shaft 72, journaled in a bearing 73 in each side of the frame 74 of the machine, the pinions meshing with toothed racks 75 on the respective sides of the carriage, the carriage being guided in its reciprocations in true lines by suitable guides 76. Movement of the carriage over the plate, laid printing face down upon the bed, causes shaving of the backing face of the printing plate in spaced-apart paths, while the plate is pressed toward the bed, the plate being then shifted to shave the remaining portions of the backing face, for reducing the printing plate to approximate uniform thickness between its printing lines and the backing surface, but preferably thicker than the finished printing plate to allow for the compression of the plate and for subsequent shavings.

For more particular description of a shaving machine employable for the purpose, reference is made to the shaving machine shown, described and claimed in Letters Patent No. 1,282,018, granted me October 15, 1918, for method of and apparatus for shaving printing plates, it being assumed that such shaving machine having a flat bed and linear shaving movement between the shaving elements and the printing plate be employed.

The printing plate in such condition is of approximate uniform density throughout, this density of backing material being exemplified by the uniform spacing of the lines representing the cross-sectioning of the plate in Figs. 2 and 3.

When the printing plate is first formed, its printing surface, that is to say, the printing lines of the printing surface are wavy in portions, or the portions of the printing surface are not in the projections of the same surface, that is, in the same plane if the printing plate be a flat plate or the same projection of a cylinder if the printing plate be a curved plate. The printing plate, when first formed, or when reduced to approximate uniform thickness throughout at its printing lines, has as a matter of fact and in printing effect undesirable irregularities in its printing surface and in thicknesses in different portions of the plate, forming undue high or low places in the printing surface, resulting in imperfect printing impressions and the practice heretofore of overlaying the tympan or underlaying the plate or the block on which the plate is mounted.

The term "projection of the same surface," and corresponding expressions throughout the description and claims, are to be under-

stood as meaning "the same plane of a flat surface", as applied to a plane surface, and "the same curved surface of the sector of a cylinder" or "cylindrical surface" as applied 5 to a curved surface. The term is employed for convenience, and avoids confusion in expression where it is desired to describe or claim both or either characters of surfaces.

In my improved method, I compress the 10 backing of the printing plate, and solidify any soft or porous spots in the plate, and press all portions of the printing surface of the printing plate toward a given surface in order to locate all portions of the printing 15 surface in the projection of the same surface, that is, in the same plane if the plate be a flat plate and into the same surface of a cylinder if the plate be a curved plate.

The printing plate, especially the backing 20 material thereof, is in my improved method therefore next compressed, preferably selectively according to the solidities of the printing portions of the printing plate. Thus the portions of the printing plate at 25 the printing portions thereof which are solid, are compressed to greater densities than those portions thereof which are provided with high-lights or intermediate solidities of printing surface. These differences in densities 30 are indicated in Fig. 4 by the differences in the closeness of the cross-sectional lines.

I accomplish this operation preferably by placing the printing plate with its printing face upon a plane hard surface, preferably of 35 greater area than the area of the printing plate, as of a resistance member 80, which may be a steel slab, (see Figs. 4 and 5), all portions of which surface are in the same projection of a given surface, and providing 40 a compressing member, exemplified at 81, preferably of greater area than the area of the printing plate, which I apply to the backing surface of the printing plate, this compressing member being provided with 45 hard contact faces acting upon the backing of the printing plate in equidistant relations throughout from the hardened surface of the resistance member coacting with the 50 printing surface of the printing plate.

Pressure is applied to cause approach between said compressing member and the coacting resistance member, to compress the printing plate between said surfaces so as to cause compression of the printing plate, 55 there hard contact faces preferably compressively acting upon the backing of the printing plate which, in practice, is usually softer or more readily compressible than the material of the printing surface of the printing plate, which is usually a printing shell. The printing surface is in any event supported by the plane hardened surface of the resistance member to prevent crushing 60 thereof or injury thereto.

65 Protuberances and recesses are located at

the back portion of the printing plate to aid in the compression of the printing plate. I prefer to employ a compressing member whose compressing surface comprises such protuberances and recesses, and in Figs. 4, 5 70 and 6 show such a member having protuberances having spaces therebetween. These protuberances or compressing areas are represented as elevations 83, between which there are depressions 84. These elevations 75 preferably have sloping sides 85 forming the walls of the depressions, the sides sloping away from each other at the respective elevations, for contracting the depressions toward their bottoms, and the depressions 80 are arranged to receive material of the backing due to the entrance into the backing of the elevations. The sloping sides of the depressions react upon the material received in the depressions to cause compressing of 85 those portions of the material of the backing received in said depressions. The sloping sides also afford relief for permitting ready removal of the compressing member after compression has taken place. 90

One of the objects of providing the raised compressing faces and coacting depressions is to permit the compressing faces to compressingly act on the backing material throughout the area of the same, and preferably to enter the backing material for exerting the compression, thereby enhancing the compressive effect by employment of less pressures, avoiding injury to the printing surface, and preventing spreading of the 100 printing plate in the direction of the plane of the plate, in order to maintain all printing lines of the printing surface in original relations in the directions of the plane of the plate to enable hair-line registry between 105 printing plates of a set of plates, especially useful in so-called multi-color work.

A printing plate is in practice, during the printing operation, subjected to greater pressures per area, at the solid portions 110 thereof, than it is at the other portions thereof, for instance, the high-light portions of the same. I therefore provide the backing of the printing plate at the solid portions thereof with greater density per area 115 than the backing portions of the printing plate at the other portions thereof for instance the high-light portions.

The compression may be accomplished by any suitable device capable of imparting substantially great pressures, for instance a hydraulic press comprising a bed 88, on which the resistance member 80 is received and upon which latter the printing surface of the printing plate is laid. (See Fig. 5). This resistance member is preferably a hardened steel plate to resist all compression by the printing plate and prevent injury to the printing lines of the printing plate. 125 The compressing member provided with the 130

compressing elevations and coacting depressions is placed upon the back of the printing plate, so as to coact with the backing material of the printing plate. A plunger 89 of 5 the press coacts with the bed thereof, its presser surface and bed surface being equidistant from each other throughout their areas, and the movable element, namely, the plunger, being guided as by guides 90, as is 10 usual in a press of this character, in true right lines perpendicular to such surfaces when applying the pressure. The applying of the pressure causes the compression of the printing plate in manner hereinbefore 15 described, and solidifies the same, including any soft or porous spots or portions therein.

I have shown the compressing elevations as having square areas. Other forms of compressing elevations may be employed, or 20 the compressing elevations may be connected with each other for forming disconnected depressions between said elevations, for instance as shown in Figs. 11 and 12, in which the compressing elevations are exemplified 25 by the continuous elevated portions 91 having the depressions 92 therein, and sloping walls 85.

I further prefer to employ compressing elevations of different areas and spacings, 30 according to the average solidities of the printing surface of the printing plate to be compressed, and prefer that the greater the amount of solid areas there are in the printing plate, the greater shall be the proportion of compressing elevations in the compressing plate. Thus, as examples, I have in Figs. 7 and 8 shown respectively a plan view and a cross-section of a portion 35 of a compressing plate which I prefer to employ when operating upon printing plates having a large amount of solids in their printing surfaces. Such plate may for instance have forty-five per cent of its area as elevation surface and fifty-five per cent 40 of its area as depressions. The outer ends 86 of the elevations may be five thirty-seconds inch square and the sloping sides 85 have an inclination of sixty degrees. In Figs. 4, 5 and 6, I have exemplified respectively a cross-section and a plan view of a 45 portion of a compressing member which I prefer to employ with a printing plate having substantially balanced areas of solids and high-lights or intermediate conditions of 50 solidities of printing surfaces, on which the area of compressing surface may amount to twenty-five per cent and the areas of depression to seventy-five per cent of the total area of the compressing member; and the 55 outer ends 86 of the elevations be one-eighth inch square, and the sloping sides 85 have an inclination of sixty degrees. I have in Figs. 9 and 10 illustrated respectively a 60 plan view and a cross section of an exemplified portion of a compressing member,

which I prefer to employ for coacting with printing plates having a preponderance of high-lights, on which the areas of the compressing faces may be twelve per cent and of the depressions between the same eighty-eight per cent of the entire area of the compressing member, and the outer ends 86 of the elevations be three thirty-seconds inch square, and the sloping sides 85 have an inclination of sixty degrees. All of the said 70 elevations may have a height of one-twentieth of an inch, and the bases of said sloping sides be spaced apart to provide the approximate areas mentioned. These examples are however exemplifications and not 75 limitations, as the areas, proportions of area and inclinations may vary within the spirit of my invention.

Further instancing desirable pressures to be employed in my improved method, and instancing a printing plate comprising an electro-deposited copper shell and a backing composed of a cast backing metal, such as hereinbefore described, comprising lead, 80 tin and antimony, it may be stated that I have found desirable pressures for instance upon a printing plate having a substantially solid printing surface, and a size ten inches by twelve inches, or one hundred and twenty square inches, to be a range of from one hundred and sixty tons to two hundred tons for the entire plate, equalling a range of from substantially one and one-third tons per square inch of printing plate to one and two-thirds tons per square inch of printing plate; that when compressing such printing plates of the given size having a medium solidity of printing surface, aggregate pressures having a range of from eighty tons to one hundred and sixty tons pressure may be employed, representing pressures having a range of from two-thirds of a ton per square inch to substantially one and one-third tons per square inch; and that when compressing said printing plates of such given size having a preponderance of light printing surface, aggregate pressures having a range of fifty tons to eighty tons may be employed, representing a range of from five-twelfths of a ton per square inch to two-thirds of a ton per square inch of printing plate. It may be stated further, that in employing my improved method on printing plates in which the backing material is very 95 hard, I have found desirable pressures for instance upon a printing plate having a substantially solid printing surface, and a size of ten inches by twelve inches or one hundred and twenty square inches, to be a range of from three hundred and fifty tons to six hundred tons for the entire plate, equaling a range of from substantially three tons per square inch of printing plate to five tons per square inch of printing plate; that when compressing such printing plates of the 100

given size having a medium solidity of printing surface, aggregate pressures having a range of from one hundred and fifty tons to three hundred and fifty tons pressure 5 may be employed, representing pressures having a range of from one and a fourth tons per square inch to substantially three tons per square inch; and that when compressing such printing plates of such given 10 size having a preponderance of high-lights, aggregate pressures having a range of from fifty to one hundred and fifty tons may be employed, representing a range of from substantially one-half to one and a quarter tons 15 per square inch of printing plate. The medians of the respective ranges of pressures have been found suitable for the averages of said characters of plates. The pressures mentioned may vary according to the character 20 of backing material and printing face employed, and are given as instances and not as limitations.

I have found, in printing plates, especially such as comprise printing shells of electro-deposited metal, and also in plates otherwise formed, that the edges or boundaries, as at 94, of printing surfaces are in practice higher or more prominent in unprepared printing plates than the printing surfaces, 25 as at 95, between such edges or boundaries. Exemplifying this condition, I have found that, for instance, the dots in high-light areas, when subjected to highly magnified inspection, are really not dots, but are inclosing circles, the inner areas of which are sunken and either do not print or print very lightly, although to the naked eye they appear as fully developed dots.

By employment of my improved method, 40 I am enabled to press the printing areas between boundary edges or lines into substantially the planes or projections of such printing boundaries or lines, so as to minimize the difference between such areas and 45 said boundary edges or lines in printing for enhancing the printing effect. By means of my invention, I further bring all portions of the printing surface into the same projection of the same surface, so as to minimize 50 the necessity for overlaying and underlying and producing highly efficient printing.

In subjecting the printing plate to the compressive actions hereinbefore described, 55 I produce greater densities in the solid portions of the printing plate than in the high-light portions of the same. In the high-light portions of the printing plate there are greater areas in the printing face which 60 are considerably depressed for avoiding printing thereof, and while all parts of the area of the printing plate are subjected to the same pressure in the compressive action upon the same, the pressures at the solid 65 portions are resisted by greater areas of con-

tact between the printing surface and the coacting resistance plate, upon which the same rests, than at the high-light or lighter printing portions of the printing plate, where greater unprinting areas are located. 70 These unprinting areas permit a portion of the metal been compressed to find relief in such unprinting areas, for causing less densities in the metal of the backing of the plate at those portions of the printing plate 75 having more open areas in their printing surface than the solid portions thereof, this relief of density varying according to the solidities of the printing portions, the high-light portions being provided with the least 80 densities.

The relief of density mentioned is received in the unprinting depressions, which are in practice increased in depth, where necessary, as by routing or otherwise, in finishing the plate, but the distance of perpendicular yield of the bottoms of these depressions toward the printing surface is slight. The distance of reception of the compression faces into the plate may be instanced as one-tenth the thickness of the plate, although this distance may vary without departing from the spirit of my invention within the scope of the appended claims. The compressive action upon the plates in my improved method is preferably greater than any compressive action on said plate by any pressures to which the printing plate is subjected in the printing operation to avoid compression of the printing plate during printing.

When printing from a plate made according to my method, therefore, those portions of the plate which are subjected to the greatest pressures per area in the printing operations are resisted by the greater densities in the printing plate, while those portions of the printing plate which are subjected to the less pressures per area in the printing operation, for instance, the high-light or lighter printing portions of the printing plate, are resisted by the portions of the printing plate of less density, providing resistances in the printing plate proportional to the printing pressures per area required for proper printing of the various printing portions of the plate.

I do not herein claim the means for effecting such pressures, having shown, described and claimed the same in a copending application, divisional hereof, filed by me in the United States Patent Office December 7, 1922, as Serial No. 605,455, for patent on improvements in means for compressing printing plates.

When the printing plate has been compressed, the backing surface thereof will have the form in the compressing face of the compressing member impressed therein, for instance forming ridges 97, as shown

in Figs. 4 and 13. I therefore next bring the printing plate to uniform thickness between its printing portions and rear supporting face by removing the superfluous 5 ridges in the backing surface thereof, for instance, by employment of a shaving machine, as hereinbefore mentioned, to take a shaving or shavings off of the backing of the same, to remove the undesirable ridges 10 therein, and reduce the printing plate to substantially uniform thickness between its printing portions and its rear supporting face.

A light proof is next taken from the printing plate so treated, this proof being taken 15 by placing the printing plate upon a hard surface, for instance, the bed 101 of a proof press (see Fig. 16), inking the same, and printing therefrom a light proof upon a 20 sheet of paper which is backed by a hard substance, for instance, the metal of a proving cylinder 102, or a surface which prevents indentation of the proof sheet, in order to disclose any surface depressions there may 25 be in the printing surface of the printing plate, suitable means being provided, as by a rack 103 and gear 104, respectively at each side of the bed and cylinder, for causing coactive movement between the bed and cylinder, the bed moving in guides 105.

If such depression or depressions be disclosed by this proof, the printing plate is placed face down upon a correcting slab, for instance of metal, having a true plane surface, those portions of the back forming the areas of the depression or depressions of the printing surface having been marked on the back, and said printing portions are pressed 35 toward the plane of the balance of the printing portions of the printing plate, so as to be in the same plane therewith. This may be accomplished by means of tools, as hereinafter indicated, the impressing surfaces of 40 which are however preferably laid out in plane.

If the plate is to be used flat, the proving and correcting are repeated in sequences, the marginal bearers and inner bearers are removed and the margin provided with suitable 50 plate-holding means, the plate again proved, and if necessary again corrected, in manner hereinafter described as to curved plates.

If a curved printing plate is to be formed, an example of which is shown, described and 55 claimed in my Patent No. 1,318,967, granted me October 14, 1919, for method of curving printing plates and printing plates curved thereby, such curving is then accomplished.

I have in Fig. 17 shown an exemplification of a plate curving machine by means 60 of which the printing plate may be curved. This machine is instance as comprising a table 106, arranged to be uniformly heated by partially immersing the same in a metal bath 107, in a melting pot 108, heated as by

gas-burners 109. A flexible steel band 110 is arranged on the table and receives a cushion 111, as a sheet of paper, thereon. The printing plate is laid printing face down upon this sheet.

Mold-sections 112, 113, are arranged to rock above the bed on bearers 114 at the respective ends of the mold-sections, for determining the distance between the arc-faces 115, with which the mold-sections are provided, and the bed, for properly distancing said arc-faces from the bed to accommodate the flexible band, the cushion sheet and the printing plate. Each side of the machine is provided with a toothed rack 117, with which gear-segments 118 at each end of the mold-sections mesh, for causing parallel movements of the mold-sections. The mold-sections are rocked toward each other with equal movements for rolling the flexible sheet and the printing plate about the arc faces of the mold-sections toward the middle of the printing plate, the mold-sections being then locked together and rocked, and cooled by the cooling influence of the mold-sections, which are hollow and provided with a cooling liquid.

The exemplified method of curving the printing plate is fully shown and described in my aforesaid Patent No. 1,318,967, although the curving by such method is not an essential of the present method, and the printing plate produced thereby, as other methods of curving the printing plate may be employed without departing from the 100 spirit of my invention within the scope of the appended claims.

When the printing plate has been curved, it is preferably again subjected to compressive action in its curved form, should it be 105 found that any change in density or thickness of the printing plate has taken place, due to the curving operation, or should both surfaces of the printing plate not be in true projections of concentric cylinders.

If desired, the curving of the printing plate and the compression of the same may take place immediately after the shaving of the rear face of the flat printing plate after compression of the same in its flat state, or if desired, the compression of the printing plate while flat may be dispensed with, and the full compression desired imparted to the plate after the same has been curved.

I have in Figs. 18 to 23 inclusive, illustrated an exemplifying machine by means of which compression of curved printing plates may be obtained. In this exemplification, there is a bed 121, which has a supporting face 122, preferably of greater area than the area of the printing plate, and harder than the printing face with which it is to coat, and preferably formed on the sector of a cylinder having the diameter of the path of the printing surface of the print-

ing plate while printing. The curved printing plate, represented at 125, is laid on this curved surface, with its printing face toward said surface. Pressure is applied for causing the printing surface to intimately contact or coat with this curved surface so as to locate the printing surface in the projection of the sector of its proper cylinder.

The backing of the printing plate is then 10 compressed, preferably on lines substantially perpendicular to the printing surface, or by pressures directed radially of said surface, and preferably in manner to maintain the distance relations, in the projection of the 15 printing surface, between the printing lines of said surface, in order to maintain the registry function of the printing plate. I have exemplified this as accomplished by means of compressing faces having compressing elevations 126, having sloping sides 85, and depressions 127, similar to the elevations 83 and depressions 84 of the compressing member 81, except that in this case, the compressing member, represented generally at 128, is arranged on the sectors of a cylinder for coacting with the curved surface at the back of the curved printing plate.

I have shown these compressing elevations 30 arranged on compressing plates 130, suitably secured to compressing bodies 131, as by a tongue and groove joint 132 between the same, or the compressing plate and its body may be formed as an integral structure. The respective compressing plates and their respective bodies compose sectors of the compression member 128, which are arranged to be moved radially with relation to the curved printing plate. In arranging 40 the compressing faces with relation to the sectors of the compressing member, I prefer that the depressions between elevations be coincident with the lines of separations between the sectors.

An exemplification of means for causing the compressing movement may comprise a ram 135, moved in a guide 136, in a frame 137 of the machine, and having wedge faces 138 thereon, arranged as sectors of frustro-cones, which coact with complementary wedge faces 139 on the sectors of the compressing member. Any suitable means may be provided for operating the ram. I have shown the same as provided with a screw 140, with 55 which a nut 141 is threaded, the nut being shown as in the hub of a gear 142. The nut is prevented from moving endwise but is permitted to rotate. A pinion 143 meshes with the gear. The pinion is on a shaft 144 journaled in bearings 145 on the frame, and having a hand-wheel 146 thereon for operating the same.

The sectors of the compressing member are provided with radially arranged guides 60 147, which are guided in guideways 148, in

aprons 149, 150, of the machine frame, the sectors being guided in similar paths at their respective ends. The sectors may at that end thereof toward which the ram moves be provided with extensions 151 and 70 additional guides 152 slidable in guideways 153. The respective sectors are at each end thereof provided with a lug 154, a spring 155 between said lug and a ledge 156 on the apron, normally urging the sector toward 75 its operating part and normally urging separation between the compressing member and the curved plate.

Means are provided for ready reception 80 of the plate between the bed and the compressing member, which is exemplified as accomplished by raising and lowering the bed, as by means of guiding the bed in guides 158 in the frame, and providing eccentrics 159, fixed to shafts 160, journaled in bearings 161 of the frame, two of these shafts being shown. The eccentrics act on contact faces 157 on the bed. Arms 162 are fixed to the shafts. A link 163 articulated at 164 with the arms, connect the arms for combined movements. One of the arms may be extended as a handle 165. Movement of the bed toward the compression member is preferably limited by stops 166 to locate the curved face of the bed at 90 such point, so that it lies in the sector of the cylinder on which the plate has been curved, or which is coincident with the desired curvature of the printing plate, and to locate this sector at such distance from 100 the frustro-cones of the ram, so that the axes of these frustro-cones and said sector will be coincident. This movement also preferably causes intimate contact between the rear face of the backing of the printing plate and the compressing member, to arrange the printing plate in its true curvature. 105

The radial movements of the sectors of the compressing member preferably then 110 take place. Such movements are substantially perpendicular to the various portions of the printing plate with which said sectors coact, the compressing face of said sectors being of such construction as to maintain the printing plate as a whole to its original dimensions and to maintain the distance relations in the projection of the printing surface, of the printing lines of said surface, as hereinbefore explained with 115 relation to the compression of flat plates. 120

The action and results of compression and solidification of the curved plate are the same as heretofore explained in connection with the compression of flat plates. The 125 portions of the curved printing plate comprising solid printing areas are compressed to greater density than the portions of the plate at which lighter printing surfaces are located. Compressing faces having various 130

shapes and areas may also be employed in compressing curved plates as explained in relation to compressing flat plates.

I do not herein claim the invention embraced in the machine herein shown and described for effecting compression of the curved printing plate, having shown, described and claimed said invention in a copending application filed by me in the 10 U. S. Patent Office December 7, 1922, Serial No. 605,455, aforesaid.

It is obvious of course that other means may be employed for causing approach and recession between the curved printing plate 15 and a compression member, or for causing compression of the curved printing plate, within the spirit of my invention and the scope of the appended claims.

The rear face of the curved printing plate 20 then has the undesirable ribs or projections 169 due to compression, removed, as by shaving.

The shaving of the inner face of the curved printing plate may be accomplished 25 by laying the curved plate in a suitable machine in a trough 170, (see Fig. 24) with the printing face of the curved plate presented to the wall of the trough, and with one edge of the plate against the longitudinally extending stop 171, and by passing a rotary facing cutter 172 lengthwise of and parallel to its axis of rotation and to the axis of the plate across the inner face 30 of the curved plate.

A machine upon which the shaving may be accomplished is fully shown, described and claimed in Letters Patent of the United States No. 1,282,013, granted me October 15, 1918, for method of and apparatus for 35 shaving printing plates.

When the curving and shaving of the printing plate have been accomplished, the marginal bearers 55 are preferably next trimmed from the plate, for instance in the 40 line of the grooves 56 between said bearers and the printing surface, which may be accomplished by passing the same over a table 174 along a trimming saw 175. (See Fig. 25.)

The edge of the plate may then be provided with a suitable attaching face for securing the plate to the plate-cylinder, accomplished manually or by machine, as for instance by means of passing the same on a 45 table 176 along the gage 177 and past a cutter 178 for shaping the edge of the plate, for instance, of bevel form, as shown at 179, (see Fig. 26), when it is desired to attach the plate to the plate cylinder by means of 50 any suitable hook or registering devices.

When the printing plate has been curved, compressed and shaved, it is preferably placed on a saddle 181 of hard metal, as of 55 steel, having an imposing face 182 arranged on the sector of a cylinder substantially co-

incident with the sector of the cylinder on which the rear or inner face of the printing plate is formed. (See Figs. 31 and 32.) The printing plate is imposed toward the saddle, as by pounding by a mallet 183 upon an imposing block 184 having a concave imposing face 185, as of hard wood, arranged on the sector of a cylinder coincident with the sector of the cylinder on which the printing surface of the printing plate is formed. The imposing face impacts the printing surface of the printing plate, the blows of the mallet on the imposing block causing recession from the projection of the printing surface of any portions thereof backed by backing material which is still porous or which imparts improper support, which recession or yielding will be disclosed by the next proof by the light appearance in the proof of those yielded portions. The backing material at the yielded portions is locally compressed by the tools hereinafter described to additionally solidify or compress this backing material.

When the printing plate has been curved, compressed and shaved, and imposed, when the imposing of the printing plate is found desirable, a proof is taken of the same between hard surfaces, so as to disclose any imperfections in the printing surface, due, for instance, to any portion or portions of the printing surface being below the projection of a given surface or below the same projection of a cylinder in which the portions of the printing surface properly placed are located. Such a proof may be obtained for instance by mounting the plate on a proof cylinder and printing a light proof therefrom upon a sheet laid upon a hard plate or sheet, for instance of metal, so as to cause the proof to be taken between hard surfaces which are equidistant, the printing plate having been suitably inked.

The proof may for instance be taken on a proof press comprising a metal plate cylinder 191, (see Fig. 27), to which the curved printing plate is suitably secured, and causing coaction therebetween and a bed 192, as by means of providing each side of the bed with a rack 193, and the plate cylinder with a gear 194 meshing therewith. The proof sheet 195 of paper is laid upon the bed, which is a plane surface, or upon a hard sheet 196 preferably of metal of uniform thickness, the printing plate having been inked, coactive movement is caused between the plate cylinder and the supporting bed for causing a light printing of the printing plate upon the proof sheet.

If such proof impression show any portion or portions of the printing plate as depressed or inside the projection of the cylinder on which the plate is formed, as by failure to print or printing too light in the proof, the curved printing plate is laid in

a trough 200, with its printing surface upon the convexly curved hardened face of the trough, which is curved with a curvature coincident with the curvature which the finished printing plate is to have, exemplified for instance as a diameter of twelve and a half inches, representing the diameter of the bearers of a plate cylinder on which the printing plate is to be mounted. The contact face of this trough for this printing surface, is preferably a hardened contact face, for instance of hardened steel. (See Figs. 28 and 29.)

That portion of the back of the printing plate which is opposite the depressed portion of the printing plate having been previously marked, this marked portion is then pressed toward the curved face of the trough. This is accomplished by means of finishing tools, exemplified in Figs. 28 and 29, and Figs. 33 to 55 inclusive, of the drawings. These tools have impact faces 201 to 218, inclusive, for the back of the plate, arranged to depress the hollows in the printing surface of the printing plate into the projection of said surface, and comprising for instance protuberances 221 having spaces 222 between them. The areas of the impact faces of the protuberances vary in size according to the duties they are to perform and the areas they are to cover. They are shown substantially full-size in the drawings. The impact faces are straight on one axis and curved on the axis at right angles thereto upon a curvature corresponding to the curvature of the inner face of the backing of the printing plate being corrected. The indicating marks 224 indicate the directions in which the faces of the tools extend in straight lines, and the indicating marks 225 indicate the directions in which the impact faces thereof are curved.

The tools are provided with handles 227 by means of which they are gripped by the hand. The impact of the tools upon the printing plate may be caused by suitable hammers, as at 228, preferably small and of little weight, depending on the duties and forces of the impacts which may be desired, for pressing the portion of the plate being corrected toward the concave block or anvil, care being taken to avoid too great a depression of the backing material.

I do not herein claim the means for correcting printing plates, embracing the small tools, saddle, anvil and coating parts, having shown, described and claimed the same in a copending application, divisional herein, filed by me in the United States Patent Office December 7, 1922, as Serial No. 695,454, for improvements in means for correcting printing plates.

The backing of the printing plate is then again shaved, in manner hereinbefore explained, for again reducing the corrected

portion, and the balance of the printing plate to proximate uniform thickness at the printing portions. The shaving thus removed usually represents a thickness of two thousandths of an inch upwards to usually about five thousandths of an inch.

The printing plate thus corrected is again proved, and if any imperfections appear, the plate is again corrected in manner just described, and the backing thereof again shaved, and these operations repeated in sequence until the proving of the printing plate shows a printing plate whose printing surfaces are throughout in the same cylindrical projection, and which at its printing portions is of uniform thickness, in printing effect, so as to avoid or minimize the necessity of overlaying or underlaying in making ready the printing plate, and providing a printing plate which is substantially ready for printing when properly placed upon the printing press.

The final shaving to which the curved plate has been subjected, is such as to reduce the curved plate to such thickness at its printing portions and such curvature at its inner or rear face, that the latter curvature will be coincident with the curvature of the plate-cylinder on which it is to be fastened for printing, and the printing surface be concentric therewith, in order that the inner or rear face of the printing plate will make intimate contact throughout its area with the periphery of the plate cylinder, and the printing surface be in printing relation throughout its printing area with the tympan, properly placed, of the printing press.

If the printing plate is provided with portions which must be removed from the printing side prior to printing the plate, for instance, interior bearers, such removal is accomplished as by routing, when the proving of the printing plates shows a printing plate of uniform printable condition, within the scope of my invention. After such removal or routing, the plate is preferably again proved and any imperfection therein corrected in manner hereinbefore described.

The printing plate, whether flat or curved may be instance to be three-sixteenths of an inch thick in its finished state, but the diameters and dimensions given are merely exemplifications, and may be altered or changed, or other diameters and dimensions substituted, within the spirit of my invention and the scope of the appended claims, or, if desired, the diameters and shapes of the printing plates may be changed after correction thereof within the scope of the appended claims.

By means of my improved method, a printing plate is obtained, having a printing surface, the printing lines of which are located in the surface of the same surface, that is the same plane, if it be a straight

plate, and the same projection of a cylinder or sector of a cylinder if the plate be a curved plate, as determined by print pressures. The tympan surface upon which the 5 sheets of paper or other material being printed are laid in the printing operation, is also in the projection of a given surface, either plane or cylindrical, and is comparatively hard, so that the printing contact is 10 what may be termed a kiss contact between the paper and ink for transferring the pigments of ink to the paper, and avoiding all rubbing contact between the paper and the ink which is incident to causing the paper 15 to be received in depressions or causing the paper to be bent over bulges in the faces of make-readies as now generally employed.

Having thus fully described my invention, what I claim as new, and desire to set 20 cure by Letters Patent, is:

1. The method of correcting a printing plate which comprises rendering the plate of uniform thickness between its printing portions and its rear supporting face throughout 25 out said printing portions as determined by printing pressures.

2. The method of correcting a printing plate which comprises subjecting said printing plate having the printing surface previously 30 formed thereon to substantial pressure to solidify its backing material to render the same free of compression by printing pressures.

3. The method of correcting a printing 35 plate which comprises compressing said printing plate throughout its printing areas by pressures in directions substantially perpendicular to said printing areas and restraining flow of the compressed portions in 40 the direction of projection of said printing surface and reducing said printing plate to equal thickness between its printing portions and its rear supporting face throughout its printing areas as determined by 45 printing pressures.

4. The method of correcting a printing plate which comprises compressing said printing plate throughout its printing surface with greater pressures per area of printing 50 surfaces than the printing pressure per area applied to said printing surface.

5. The method of correcting a printing plate which comprises compressing the backing material of said printing plate by indentation while confining said backing material as a whole in directions parallel with the plane of said printing plate, and reducing said printing plate to equal thickness between its printing portions and its rear 55 supporting face throughout its printing portions.

6. The method of correcting a printing plate which comprises bringing the printing surface of the printing lines and areas

throughout the printing plate into a plane 65 equi-distant from the rear supporting surface of the printing plate and bringing these two surfaces respectively within the same projection of a given surface as determined by printing pressures. 70

7. The method of correcting a printing plate which comprises bringing the supporting backing surface and the printing lines equidistant from each other in projections respectively of two spaced-apart surfaces as 75 determined by printing pressures.

8. The method of correcting printing plates which comprises removing undesirable irregularities in the printing surface of said plate, as determined by printing effect, 80 by compressive pressure upon said printing plate throughout the printing surface thereof to compress said printing plate to a density greater than the density by printing pressure upon said printing plate. 85

9. In the art of correcting printing plates, the compressing of the printing plate to a state of solidity throughout the printing area thereof as determined by printing pressures. 90

10. In the art of correcting printing plates, the compressing of the backing material of the printing plate to a state of differential solidity determined by the solidities of the printing surface of said printing plate. 95

11. In the art of correcting printing plates, the compressing of the printing plate to a state of substantial solidity by substantially equal pressure applied throughout 100 the area of the plate, and then, locally solidifying those portions of less solidity than the desired solidity.

12. The method of correcting a printing plate which comprises compressing the printing plate substantially immediately after casting the same by indentation and relief areas at the rear face of said printing plate, and reducing said printing plate to equal thickness between its printing portions 110 and its rear supporting face throughout its printing portions.

13. The method of correcting a printing plate which comprises rendering the printing plate of uniform thickness and of different densities related to its varied printing portions by uniform applied pressure applied throughout its printing area. 115

14. The method of correcting a printing plate which comprises rendering the body of the printing plate of greater density at the more solid portions of its printing surface and of less density at the lighter portions of its printing surface. 120

15. The method of correcting a printing plate which comprises applying sufficient pressure thereto to cause compression of its backing material and to restrain lateral 125

movement of said backing material during said compression, and reducing said printing plate to uniform thickness between its printing portions and its rear supporting face throughout its printing portions gauged by printing pressures.

16. The method of correcting a printing plate which comprises compressing the same between surfaces which are equidistant at various printing portions of said plate to produce densities at said various printing portions determined by the solidities of said printing portions.

17. The method of correcting a printing plate which comprises pressing the sunken printing portions of the printing surface thereof located between printing edges of printing characters into the plane of said printing edges by compression of the backing material of said printing plate with greater pressure than the printing pressures upon said printing edges.

18. The method of correcting a printing plate provided with printing areas and with unprinting areas, applying pressure to said printing plate to compress the backing material of said printing plate with local flow of said backing material toward said unprinting areas to provide relief of density of said printing plate in said printing areas, and reducing said printing plate to even thickness between its printing portions and its rear supporting face at its printing portions.

19. The method of correcting a printing plate which comprises applying greater pressure per area of printing surface of said printing plate than the printing pressure per area which such plate must withstand, and compressing the backing material of said printing plate with different densities gauged by the different solidities of said printing surface, for imparting greater densities to said backing material at the more solid portions of said printing surface and imparting less densities to said backing material at the less solid portions of said printing surface, and reducing said printing plate to equal thickness between its printing portions and its rear supporting face throughout its printing areas.

20. The method of correcting a printing plate which comprises compressing said printing plate by indentation and relief areas to restrain lateral movement of the material of said plate, and reducing said printing plate to equal thickness between its printing portions and its rear supporting face throughout its printing portions.

21. The method of correcting printing plates which comprises compressing the backing material of said printing plate by indentation and relief areas having sloping walls to confine and aid in compression of

material received in said relief areas, and reducing said printing plate to equal thickness between its printing portions and its rear supporting face throughout its printing portions.

22. The method of correcting a printing plate which comprises compressing said printing plate by indentation and relief areas by pressures applied in directions substantially perpendicular to the printing surface of said printing plate with the walls of said relief areas reacting upon the material received in said relief areas to compress said material, and reducing said printing plate to equal thickness between its printing portions and its rear supporting face throughout its printing portions.

23. The method of correcting a printing plate which comprises compressing said printing plate by indentation and relief areas applied to the rear face of said printing plate while the entire printing surface of said printing plate is supported by a face wholly located in the projection of a given surface and in manner to maintain the printing lines of said printing plate in spaced relations in the plane of said printing plate.

24. The method of correcting a printing plate which comprises compressing said printing plate by indentation and relief areas applied to the rear face of said printing plate while the entire printing surface of said printing plate is supported by a face wholly located in the projection of a given surface whereby to form depressed and raised areas in said rear face and reducing the rear supporting face of said printing plate to an even surface.

25. The method of correcting a printing plate which comprises applying sufficient pressures to the back of the printing plate to cause straightening of the sunken printing portions between printing lines of individual printing characters in the printing surface of said printing plate to locate said sunken printing portions and said printing lines in the projection of a common surface.

26. The method of correcting a printing plate comprising printing portions of different solidities and having printing portions and unprinting portions at the printing side of said printing plate, applying pressure to said printing plate to cause different densities in the backing material thereof according to the solidities of said printing portions by means of pressure per area applied to said printing plate greater than the printing pressure per area which said printing plate is to withstand, in manner to cause relief of said backing material at printing portions of less solidities in said printing surface.

27. The method of correcting a printing plate comprising printing portions of differ-

ent solidities and having printing portions and unprinting portions at the printing side of said printing plate, applying pressure to said printing plate to cause different densities in the backing material thereof according to the solidities of said printing portions by means of pressure per area applied to said printing plate greater than the printing pressure per area which said printing plate is to withstand, in manner to cause relief of said backing material at printing portions into unprinting portions and printing areas or less solidities in said printing surface, and reducing said printing plate to even thickness between its printing portions and its rear supporting face throughout its printing portions.

28. The method of correcting a printing plate comprising printing portions of different solidities and having printing portions and unprinting portions at the printing side of said printing plate, applying pressure to said printing plate to cause different densities in the backing material thereof according to the solidities of said printing portions by means of pressure per area applied to said printing plate greater than the printing pressure per area which said printing plate is to withstand, in manner to cause relief of said backing material at printing portions into unprinting portions and printing areas of less solidities in said printing surface, said compression effected by indentation and relief areas at the rear face of said plate in manner to maintain the printing lines of said plate in spaced relations in the plane of said plate.

29. The method of correcting a printing plate comprising printing portions of different solidities and having printing portions and unprinting portions at the printing side of said printing plate, applying pressure to said printing plate to cause different densities in the backing material thereof according to the solidities of said printing portions by means of pressure per area applied to said printing plate greater than the printing pressure per area which said printing plate is to withstand, in manner to cause relief of said backing material at printing portions into unprinting portions and printing areas of less solidities in said printing surface, said pressures applied by indentation and relief areas provided with sloping walls at the rear face of said printing plate to retain the dimensions of said printing plate at its printing surface, and said sloping walls forming relief areas reacting on the backing material received therein to compress said backing material.

30. The art of correcting printing plates respectively having a preponderance of solids of printing surface, a preponderance of highlights of printing surface, and a preponderance of intermediate states of printing sur-

face, by the compressive action of compressing elevations and depressions having different areas determined by the respective preponderances of the printing surfaces of said printing plates.

31. The art of correcting printing plates respectively having a preponderance of solids of printing surface, a preponderance of highlights of printing surface, and a preponderance of intermediate states of printing surface, and respectively having unprinting portions in the printing sides thereof, by the compressive action of compressing elevations and depressions having different areas determined by the respective preponderances of the printing surfaces of said printing plates, and providing relief of density in unprinting portions of said plates varying and determined by the preponderances in said printing surfaces.

32. The method of correcting a printing plate which comprises compressing said printing plate to withstand printing pressures, and locally pressing the rear face of said printing plate to press sunken portions of the printing surface thereof into the projection of the balance of said printing surface as determined by printing pressures, and reducing said printing plate to equal thickness between its printing portions and its rear supporting face throughout at its printing portions as determined by printing pressures.

33. The method of correcting a printing plate provided with marginal bearers which comprises compressing said printing plate by indentation and relief areas at the rear face of said plate whereby to form depressed and raised areas in said rear face of said plate and reducing the rear supporting face of said printing plate to an even supporting surface; and locally pressing the rear face of said printing plate to press sunken portions of the printing surface thereof into the projection of the balance of said printing surface as determined by printing pressures and reducing said rear supporting face to an even supporting surface, in repeated sequences; and, removing said marginal bearers.

34. The method of correcting a printing plate provided with marginal bearers which comprises compressing said printing plate by indentation and relief areas at the rear face of said plate whereby to form depressed and raised areas in said plate and reducing the rear supporting face of said printing plate to an even supporting surface; and locally pressing the rear face of said printing plate to press sunken portions of the printing surface thereof into the projection of the balance of said printing surface as determined by printing pressures and reducing said rear supporting face to an even supporting surface, in repeated se-

quences; removing said marginal bearers, and providing the margins of said printing plate with securing edges.

35. The method of correcting a printing plate which comprises compressing said printing plate, reducing said printing plate to substantially equal thickness between its printing portions and its rear supporting face at its printing portions; and proving said printing plate between substantially unyielding surfaces, pressing those portions of said printing plate which prove with too light an impression toward said printing surface, and reducing said printing plate to equal thickness between its printing portions and its rear supporting face at its printing portions, for correcting said printing plate, to impart to it a printing surface which is throughout in the projection of the same surface and to reduce said printing plate at said printing surfaces throughout to the same thickness between its printing portions and its rear supporting face as determined by printing pressures between substantially unyielding surfaces respectively in the projection of the same surface.

36. The method of correcting a printing plate which comprises compressing said printing plate by indentation and relief areas at the rear face of said printing plate whereby to form depressed and raised areas in the rear supporting face of said printing plate, reducing said rear face to an even supporting surface, proving said printing plate between substantially unyielding surfaces; and pressing those portions of said printing plate which prove with too light an impression, toward the printing surface of said printing plate by pressure upon said rear face, reducing said rear supporting face to an even supporting surface, and reproving said printing plate between substantially unyielding surfaces, in repeated sequences.

37. The method of correcting a printing plate provided with bearers which comprises compressing said printing plate including said bearers by indentation and relief areas at the rear face of said plate, whereby to form depressed and raised areas in said rear face, reducing the rear supporting face of said printing plate to an even supporting surface, proving said printing plate between substantially unyielding surfaces, pressing those portions of said printing plate which print with too light an impression toward said printing surface, reducing said printing plate to equal printing thickness between its printing portions and its rear supporting face throughout the area of the printing portions of said printing plate including said bearers, and removing said bearers.

38. In the method of correcting printing

plates the forming of the printing plate of proximate uniform thickness at its printing portions, compressing said printing plate, and reducing the rear supporting face thereof to a substantially even supporting surface; and proving said printing plate and pressing those portions of the printing plate which prove with too light an impression into the projection of the printing surface of said printing plate, in repeated sequences.

39. In the method of correcting printing plates, approximately forcing the printing surface of said printing plate into the projection of a given surface by imposing upon the rear surface thereof toward an anvil having an imposing surface located in the projection of said given surface, forming the printing plate of proximate uniform thickness at its printing portions, compressing said printing plate, and reducing the rear supporting face thereof to a substantially even supporting surface; and proving said printing plate and locally pressing those portions of the printing plate which prove with too light an impression into the projection of the printing surface of said printing plate, in repeated sequences.

40. The method of correcting printing plates which comprises compressing backing material of the printing plate and reducing the printing plate to substantially uniform thickness at its printing portions, with the supporting backing surface and the printing surface thereof located in two spaced-apart projections of two spaced-apart surfaces; and taking a light proof of said printing plate, marking on the back of the printing plate those portions of the printing plate which prove too light, locally pressing said marked portions toward the printing surface to locate the printing lines of said marked portions of said printing surface in the projection of the balance of said printing portion of said printing plate, as determined by proving pressures, and shaving the back of said printing plate to reduce said printing plate throughout to substantially equal thickness between its printing portions and its rear supporting face at its printing portions, in repeated sequences.

41. The method of correcting printing plates which comprises compressing backing material of the printing plate and reducing the printing plate to substantially uniform thickness between its printing portions and its rear supporting face at its printing portions with the supporting back surface and the printing surface thereof located in two spaced-apart projections of two spaced-apart surfaces; and taking a light proof of said printing plate, locally pressing those portions of the printing plate which prove with too light an im-

pression toward the balance of the printing surface by protuberances whose pressing surfaces are located in projections parallel with said backing to locate the 5 printing lines of said portions which prove too light in the projection of the balance of said printing portion of said printing plate, as determined by proving pressures, and shaving the back of said printing plate to 10 reduce said printing plate throughout to substantially equal thickness between its printing portions and its rear supporting face at its printing portions, in repeated sequences.

15 42. The method of correcting a printing plate which comprises rendering the same of uniform thickness and of different densities at its varied printing portions, proving said printing plate between substantially 20 unyielding surfaces, pressing those portions thereof which prove with too light an impression toward the printing surface of said printing plate, and reducing said printing plate to uniform thickness between its 25 printing portions and its rear supporting face throughout its printing portions, as determined by printing pressures.

43. The method of correcting a printing plate which comprises compressing the same 30 to different densities at its printing portions of different solidities to cause greater densities at the more solid portions and less densities at the more open portions of said printing surface, pressing those portions of said 35 printing plate which prove with too light an impression toward its printing surface, and reducing said printing plate to equal thickness between its printing portions and its rear supporting face throughout its 40 printing areas.

44. The method of correcting a printing plate which comprises curving said printing plate, compressing said curved printing plate, and reducing said curved printing plate to equal thickness between its printing portions and its rear supporting face throughout its printing portions determined by printing pressures.

45. The method of correcting a printing plate which comprises curving said printing plate, compressing said curved printing plate by applying pressure to said curved printing plate in directions substantially perpendicular to the various portions of its 55 printing area, and reducing said printing plate to equal thickness between its printing portions and its rear supporting face throughout its printing area as determined by printing pressures.

60 46. The method of correcting a printing plate which comprises compressing said printing plate while flat by indentation and relief areas at the rear face of said printing plate whereby to form depressed and raised 65 areas in the rear supporting face of said

printing plate, reducing said rear face to an even supporting surface, curving said printing plate, compressing said curved printing plate by indentation and relief areas at the rear face of said curved plate whereby to 70 form depressed and raised areas in said rear face, and reducing said rear supporting face to an even supporting surface.

47. The method of correcting a curved printing plate having an outer printing 75 surface which comprises supporting said outer printing surface on a curved face, applying a curved face to the inner face of said curved printing plate, said curved faces being concentric, and causing approach between said curved faces to compress said printing plate.

48. The method of correcting a curved printing plate having an outer printing surface which comprises supporting said outer 85 printing surface and applying pressure upon the inner surface of said curved plate in directions substantially radial with relation to said curved printing plate.

49. The method of correcting a curved 90 printing plate having an outer printing surface which comprises applying pressure upon the inner face of said curved printing plate by a plurality of pressure means respectively moving in lines radial to said 95 curved printing plate to apply said pressure.

50. The method of correcting a curved printing plate having an outer printing surface which comprises pressing said curved 100 printing plate between substantially concentric surfaces to determine the curvature of said printing plate, and then compressing said curved printing plate between said surfaces by relative movement between said 105 surfaces.

51. In the art of correcting a curved printing plate, the applying of compressing pressure upon said curved printing plate from a point within the projection of a 110 cylinder of which the curved sector of said printing plate is a part.

52. The method of correcting a curved printing plate which comprises pressing said curved printing plate between substantially concentric surfaces, the inner one of which comprises indentation and relief areas, then causing approach between said surfaces whereby said indentation areas are pressed into the backing of said printing plate, and reducing said printing plate to equal thickness between its printing portions and its rear supporting face throughout its printing portions.

53. The method of correcting a curved printing plate comprising bearers, which comprises pressing said curved printing plate including said bearers between substantially concentric surfaces, the inner one of which comprises indentation and relief 125 areas.

areas, then causing approach between said surfaces whereby said indentation areas are pressed into the backing of said printing plate, reducing said printing plate to equal thickness between its printing portions and its rear supporting face throughout its printing portions, and removing said bearers.

54. The method of correcting a curved printing plate which comprises pressing said curved printing plate between substantially concentric surfaces, the inner one of which comprises indentation and relief areas, then causing approach between said surfaces whereby said indentation areas are pressed into the backing of said printing plate, reducing said printing plate to equal thickness between its printing portions and its rear supporting face throughout its printing portions, and providing the marginal edges of said plate with securing faces.

55. The method of correcting a curved printing plate which comprises pressing said curved printing plate between substantially concentric surfaces, the inner one of which comprises indentation and relief areas, then causing approach between said surfaces whereby said indentation areas are pressed into the backing of said printing plate, reducing said printing plate to equal thickness between its printing portions and its rear supporting face throughout its printing portions, locally pressing portions of said printing plate outwardly into the projection of the printing surface of said printing plate, and reducing said printing plate to equal thickness between said printing portions and its rear supporting face throughout its printing portions.

56. The method of correcting a curved printing plate comprising bearers, which comprises pressing said curved printing plate including said bearers between substantially concentric surfaces, the inner one of which comprises indentation and relief areas, then causing approach between said surfaces whereby said indentation areas are pressed into the backing of said printing plate, reducing said printing plate to equal thickness between its printing portions and its rear supporting face throughout its printing portions, removing said bearers, locally pressing portions of said printing plate outwardly into the projection of the printing surface of said printing plate, and reducing said printing plate to equal thickness between its printing portions and its rear supporting face throughout its printing portions.

57. The method of correcting a curved printing plate which comprises pressing said curved printing plate between substantially concentric surfaces, the inner one of which comprises indentation and relief areas, then causing approach between said surfaces whereby said indentation areas are pressed

into the backing of said printing plate, reducing said printing plate to equal thickness between its printing portions and its rear supporting face throughout its printing portions, providing the marginal edges of said curved printing plate with securing faces, locally pressing portions of said printing plate outwardly into the projection of the printing surface of said printing plate, and reducing said printing plate to equal thickness between its printing portions and its rear supporting face throughout its printing portions.

58. The method of correcting a curved printing plate which comprises compressing the backing of the printing plate and reducing the printing plate to equal thickness between its printing portions and its rear supporting face throughout its printing portions; and proving said curved printing plate, pressing those portions thereof which prove with too light an impression toward its printing surface, and reducing said curved printing plate to equal thickness between its printing portions and its rear supporting face throughout its printing portions, in repeated sequences.

59. The method of correcting a curved printing plate comprising bearers, which comprise compressing the backing of the printing plate, reducing the printing plate to equal thickness between its printing portions and its rear supporting face throughout its printing portions, and removing said bearers; and proving said curved printing plate, pressing those portions thereof which prove with too light an impression toward its printing surface, and reducing said curved printing plate to equal thickness between its printing portions and its rear supporting face throughout its printing portions, in repeated sequences.

60. The method of correcting a curved printing plate which comprises compressing the backing of the printing plate, reducing the printing plate to equal thickness between its printing portions and its rear supporting face throughout its printing portions, and providing the margins of said curved printing plate with attaching faces; and proving said curved printing plate, pressing those portions thereof which prove with too light an impression toward its printing surface, and reducing said curved printing plate to equal thickness between its printing portions and its rear supporting face throughout its printing portions, in repeated sequences.

61. The method of correcting curved printing plates which comprises compressing backing material of the plate and reducing the printing plate to substantially uniform thickness at its printing portions with the curved back supporting surface and the curved printing surface thereof substantially located in two spaced-apart cylin-

- 65
drical projections of two concentric cylinders; and taking a light proof of said curved printing plate, locally pressing the back of those portions of the curved printing plate
6 which prove with too light an impression toward the balance of said printing surface by spaced-apart protuberances whose impact surface is arranged on an arc of a cylinder substantially concentric with said curved
10 printing plate to locate the printing lines of said portions which prove too light in the cylindrical projection of the balance of said printing portion of said curved printing plate, as determined by proving pressures,
15 and shaving the back of said curved printing plate to reduce said curved printing plate between its printing portions and its rear supporting face throughout to substantially equal thickness at its printing portions.
20
62. The method of correcting curved printing plates, which comprises the local pressing of a printing portion in said curved printing plate toward the projection of the
25 curved printing surface of said curved printing plate as a whole by an impact area having recesses therein and of substantially less area than the area of said printing surface and substantially concentric with the projection of a sector of the cylinder in which said printing surface lies, then shaving the inner face of said printing plate upon a curvature concentric to said sector, whereby to reduce said curved printing plate to equal
30 thickness at its printing portions.
35
63. The method of correcting curved printing plates which comprises the local pressing of a printing portion in said curved printing plate substantially less than the
40 whole of the printing surface of said plate toward the projection of said printing surface as a whole by an indenting correcting face of substantially less area than the area of said printing surface and having protuberances whose impact faces are substantially concentric with the projection of a sector of the cylinder in which said printing surface lies.
45
64. The method of correcting curved printing plates, which comprises the local pressing of printing portions in said plate toward the projection of the curved printing surface of said curved printing plate as a whole by indenting correcting faces of different areas and of substantially less area than the area of said printing surface and substantially concentric with the projection of a sector of the cylinder in which said printing surface lies.
50
65. The method of correcting curved printing plates, which comprises the local pressing of printing portions in said plate toward the projection of the curved printing surface of said curved printing plate as a whole by indenting correcting faces of different areas and of substantially less area than the area of said printing surface and substantially concentric with the projection of a sector of the cylinder in which said printing surface lies, then shaving the inner face of said curved printing plate upon a curvature concentric with said curved printing surface whereby to reduce said curved printing plate to equal thickness at its printing portions.
70
66. The method of correcting curved printing plates, which comprises proving the curved printing surface of said curved printing plate between substantially unyielding surfaces, locally pressing those printing portions in said plate which prove too light toward the projection of said curved printing surface as a whole by an indenting correcting face of substantially less area than the area of said printing surface and having protuberances whose impact faces are substantially concentric with the projection of a sector of the cylinder in which said printing surface lies, and then reducing said printing portions to equal thickness between its printing portions and its rear supporting face.
80
67. The method of correcting curved printing plates, which comprises proving the curved printing surface of said curved printing plate between substantially unyielding surfaces, locally pressing those printing portions in said plate which prove too light toward the projection of said curved printing surface as a whole by an indenting correcting face of substantially less area than the area of said curved printing surface and substantially concentric with the projection of a sector of the cylinder in which said printing surface lies, reducing said printing plate to equal thickness between its printing portions and its rear supporting face.
85
68. The method of correcting curved printing plates, which includes proving the curved printing surface of said printing plate, locally pressing the printing portion in said curved printing plate which proves too light toward the projection of said curved printing surface while said curved printing plate is supported on an unyielding concavely curved surface which is substantially the sector of a cylinder, shaving the inner face of said curved printing plate to reduce said curved printing plate to equal thickness
90

125

between its printing portions and its rear supporting face at its printing portions, imposing said printing portions by pounding pressure of a concave imposing face upon said curved printing surface while said curved printing plate is supported on an unyielding convex surface, said last-named concave face and said last-named convex surface being substantially concentric, proving said printing plate, and locally pressing the printing portion in said curved printing plate which proves too light by said proof outwardly toward the projection of the printing surface of said curved printing plate as a whole, and shaving the curved inner face of said curved printing plate, whereby to reduce said curved printing plate to equal thickness between its printing portions and its rear supporting face at its printing portions, as determined by printing pressures.

39. The method of correcting curved printing plates having curved printing surfaces arranged on the sector of a cylinder, which includes proving the curved printing surface of said curved printing plate between substantially unyielding surfaces, locally pressing the printing portion in said curved printing plate which proves too light by pressure areas having relief areas therein and arranged on the sector of a cylinder concentric to said curved printing surface, and of substantially less area than the area of said printing surface toward the projection of said curved printing surface while said curved printing surface is supported on an unyielding concavely curved surface which is substantially the sector of a cylinder, shaving the inner face of said curved printing plate to reduce said curved printing plate to equal thickness at its printing portions, imposing said printing portions by pounding pressure of a concave imposing face concentric with said printing surface upon said curved printing surface while said curved printing plate is supported on an unyielding convex surface concentric with said curved printing surface, proving said printing plate, and locally pressing the printing portion in said curved printing plate which proves too light by said proof by pressure areas such as said first-mentioned pressure areas toward the projection of the printing surface of said curved printing plate as a whole, and shaving the curved inner face of said curved printing plate, whereby to reduce said curved printing plate to equal thickness at its printing portions, as determined by printing pressures.

40. A printing plate having a backing solidified throughout the printing portions of the printing plate by pressure and rendered of uniform thickness between its

printing portions and its rear supporting face at its printing portions.

71. A printing plate rendered solid at its printing portions by pressure throughout the area of said printing portions and by pressures applied locally at the more yielding portions of said printing portions.

72. A printing plate whose rear supporting face and printing surface are each in the projection of a given surface, said surfaces spaced apart the uniform thickness of said printing plate at its printing portions, as gauged by printing pressures.

73. A printing plate the material of which is compressed to greater density than the density of compression caused by the printing pressure on said printing plate and whose printing portions are of equal thickness and unyielding during printing.

74. A printing plate whose backing material is compressed, after the printing characters have been formed on said printing plate, by pressure sufficiently great to make said backing material of a density sufficient to resist printing pressures and unyielding during printing.

75. A printing plate the backing whereof has greater density at the solid portions of its printing surface and less density at the high light portions of its printing surface.

76. A printing plate which is of uniform thickness at its various printing portions and whose backing is of different densities at portions of its printing surface having different solidities.

77. A printing plate compressed, after formation of the printing characters thereon, to greater density than the density imparted by printing pressures and to a state unyielding during printing.

78. A printing plate of uniform thickness between its printing portions and its rear supporting face at its printing portions and of different densities substantially proportional to the solidities of its printing surfaces.

79. A printing plate whose backing material is compressed, after formation of the printing characters on said printing plate, by pressure sufficiently great to make said backing material of a density sufficient to resist printing pressures and to make the same unyielding during printing, and whose rear supporting face and printing surface are in the projections of separated surfaces as determined by printing pressures.

In testimony whereof, I have hereunto signed my name in the presence of two subscribing witnesses.

LESLIE W. CLAYBOURN.

In presence of--

L. A. WESTBROOK,
JOHN A. HANSON.
